[57] CLAIM

The ornamental design for a coffee dispenser, substantially as shown and described.

DESCRIPTION

FIG. 1 is a perspective view of the coffee dispenser showing my novel design;

FIG. 2 is a top plan view of the coffee dispenser;

FIG. 3 is a left side view of the coffee dispenser drawn from the same position as the view shown in FIG. 1;

FIG. 4 is a right side view of the coffee dispenser.

FIG. 5 is a front view thereof. The rear is plain and unornamented.
